UNITED STATES PATENT OFFICE.

MAURICE RANDOLPH LEAMAN, OF PITTSBURGH, PENNSYLVANIA.

STRAIGHT-EDGE.

1,080,225.

Specification of Letters Patent.

Patented Dec. 2, 1913.

Application filed February 9, 1911. Serial No. 607,641.

To all whom it may concern:

Be it known that I, MAURICE R. LEAMAN, a citizen of the United States, residing at Pittsburgh, in the county of Allegheny and 5 State of Pennsylvania, have invented certain new and useful Improvements in Straight-Edges; and I do hereby declare the following to be a full, clear, and exact description of the invention, such as will enable others skilled in the art to which it 10 pertains to make and use the same.

This invention relates to improvements in straight-edges, and is more particularly related to devices of this character designed 15 for use by paper-hangers.

In the use of straight-edges by paper-hangers difficulty is experienced in maintaining the implements in alined position upon the paper; slipping of the implement frequently occurs, and this results in imperfect trimming. Moreover, the straight-edges commonly employed are unprotected, by reason of which they become more or less impaired by handling, the edges becoming 25 roughened, and thereby causing a roughened line of cut.

The present invention, therefore, aims to provide a straight-edge the construction of which is such as to prevent slipping when 30 the same is placed in position for trimming the paper, thus safe-guarding the paper against irregular cut, and also reducing the degree of pressure necessary for holding the straight-edge in position.

35 Furthermore, the invention aims to provide a straight-edge having means for protecting the guide edge thereof, thereby maintaining the latter against becoming roughened and insuring a regular line of cut.

40 Having these general objects in view, and others which will appear as the nature of the improvements is better understood, the invention consists substantially in the novel construction, combination and arrangement 45 of parts hereinafter fully described, illustrated in the accompanying drawings, and pointed out in the appended claims.

In the drawings—Figure 1 is a perspective view of a straight-edge constructed in 50 accordance with and embodying the herein-described invention. Fig. 2 is an end elevation thereof.

55 Referring in detail to the drawings, the numeral 1 designates the body of the herein-described straight-edge. This is prefer-

ably formed of wood, and may be of any desired width and length. At the edge of the body 1 which constitutes the guide for the knife, said edge is provided with a metallic facing 2, preferably a brass strip, the latter being secured to the body 1 through the medium of screws 3, or other suitable fastening devices. This facing covers the entire edge of the body 1, and extends throughout the length of the latter, and mounted in proximity to the facing 2, and over-lying the edge of the facing, is a metallic contact strip 4 secured to the face of the body 1 which is designed to lie against the paper during the trimming operation. The strip 4 is held in position upon the body 1 by screws 5, or other suitable fastening devices, and it will be observed that the body 1 is rabbeted or cut away for the reception of said strip 4. This construction provides a shoulder 6 75 against which the inner edge of the strip 4 abuts, the outer edge of said strip lying flush with the outer face of the strip 2, and being alined therewith. By reason of the shoulder 6 the strip 4 is maintained in rigid 80 position, and always remains alined with the strip 2, and the face of the latter and the outer edge of the strip 4 constitute substantially a continuous surface along which the knife may be drawn in the trimming operation. 85

It is to be observed that the face of the body 1 which lies against the paper inclines from its edges toward its center. Therefore, the contact strip 4 lies in an inclined position, and while the outer edge of the strip 4 will contact with the paper, the inner edge of said strip will be out of contact therewith. This is also true of the other edge of the body 1, so that in lieu of the entire 95 width of the body resting upon the paper, actual contact only occurs at the edges of the device.

Extending from the shoulder 6 to the edge of the body 1 which is opposite to that at 100 which the strips 2 and 4 are located, is a facing of felt 7, or other suitable material. This facing acts as a resistant to lateral slipping of the straight-edge, the character of the material causing the straight-edge to 105 adhere to the paper. Hence, the pressure necessary to prevent the straight-edge slipping is materially reduced.

In the use of the herein-described straight-edge the same is placed upon the paper to 110

be trimmed with the concaved face immediately next to the paper. The felt 7 and the contact strip 4 rest on the paper, and when the line of cut has been determined 5 the knife is drawn along the facing strip 2 and the outer edge of the contact strip 4, which strips being of metal insure a regular cut. The lateral pressure incident to the movement of the knife is resisted by the adherence of the felt facing 7 with the paper, 10 so that slipping of the straight-edge is prevented and a regular cut insured.

By making the face of the body 1 concave the edges only of the straight-edge are 15 brought into contact with the paper, and by providing the metallic strips 2 and 4, and arranging them in juxtaposition, the guide-edge is efficiently protected against becoming roughened, so that an even line of cut 20 is produced.

The contact strip 4 is preferably of steel, and this, therefore, provides not only an exceedingly hard surface for resisting the great amount of wear incident to the movement of the straight-edge along the guide-edge thereof, but said contact strip also 25 serves to protect the face of the wooden body 2 at said guide edge, as indicated. By positioning the contact strip 4 at the edge 30 of the contact face of the body edge which is adjacent to the strip 2, said body is weighted at this edge, so that it renders the device as an entirely more binding at the cutting edge, and very little pressure is 35 therefore necessary to hold the straight-edge

in position upon the paper which is being cut.

Having thus described the invention, what is claimed as new, and desired to be secured by Letters Patent, is:

1. A device of the class described, comprising a body, a metallic facing for the guide edge thereof, and a metallic protective contact strip covering the contact face of the body at its guide edge, said contact strip 45 being in registry with said metallic facing and serving to weight the body at the guide edge to reduce thereby the pressure necessary for holding the device in operative position.

2. A device of the class described, comprising a body, a metallic facing for the guide edge thereof, and a metallic protective contact strip covering the contact face of the body at its guide edge, said contact strip 55 being in registry with said metallic facing and serving to weight the body at the guide edge to reduce thereby the pressure necessary for holding the device in operative position, said body having a shoulder against 90 which the inner edge of said contact strip abuts, whereby the latter is held in alignment with said metallic facing.

In testimony whereof I affix my signature, in the presence of two witnesses.

MAURICE RANDOLPH LEAMAN.
